UNITED STATES PATENT OFFICE.

ERNEST L. CONDON, OF MEDWAY, MASSACHUSETTS, ASSIGNOR TO UNITED SODA FOUNTAIN COMPANY, OF BOSTON, MASSACHUSETTS, A CORPORATION OF MASSACHUSETTS.

DETACHABLE-COVER CONSTRUCTION.

1,415,148.

Specification of Letters Patent. Patented May 9, 1922.

Application filed January 3, 1920. Serial No. 349,281.

To all whom it may concern:

Be it known that I, ERNEST L. CONDON, a citizen of the United States, and resident of Medway, in the county of Norfolk and 5 State of Massachusetts, have invented new and useful Improvements in Detachable-Cover Constructions, of which the following is a specification.

This invention relates to a separable hinge 10 connection for a cover and receptacle, and while applicable to covered receptacles generally, it is particularly designed for the cover of an ice box or chest forming part of a soda fountain installation.

15 In the accompanying drawings which illustrate a preferred embodiment of the invention—

Fig. 1 is a fragmentary view, in perspective with the cover open;

20 Fig. 2 is a plan view of the cover and receptacle top; and

Fig. 3 is a section on line 3—3 of Fig. 2.

4 indicates the top of the ice box or other chest or receptacle, provided with an opening 5, herein shown as rectangular. 6 is the cover, preferably made of a thin metal plate large enough to overlap the margin of the box top 4 around the aperture 5 excepting at the hinged edge, and, if desired, providing 30 with a wall 7 of heat insulating material on its under side.

A pair of cover positioning members 8 are fixed at each corner of the opening 5 and extend into the opening. Each member 8 is made of sheet metal with a plate 9 extending under the receptacle top 4 and fastened thereto, and an extension 10, spaced a little from the edge of opening 5 to form therewith a slot 11. The two slots 11 of the 40 two similar members 8 face each other. The free or outer edge of each member 8 is bent down as shown at 12, and the inner edge of the extension 10 is similarly bent down as shown at 13, thus forming a substantially 45 triangular extension adjacent one side of the slot 11.

On the under side of the lid or cover 6 is secured a tongue or projection 14 having a downwardly offset shoulder 15 to permit the tongue to extend under the box top 4 when the cover is closed. The tongue 14 extends between the two slots 11 and fits loosely therein. Thus the slots at one side of the opening 5 engage the tongue 14 and

position the cover 6 with relation to the 55 opening whether the cover is open or closed.

When the cover is opened it swings on its edge, which rests on a fixed part adjacent the opening, namely, the margin of the receptacle top in the construction herein shown, until the tongue 14 comes against the surfaces 13 on the extensions 10, by which it is stopped. The cover will thus be supported in open and upstanding position as illustrated in Fig. 1 and in broken lines in 65 Fig. 3. When the cover is closed the downwardly offset tongue 14 will swing away from the stops 13 and underneath the box top 4 to the position indicated in Fig. 2, and in solid lines in Fig. 3. In all positions of 70 the cover the tongue and spaced slots 11 will hold the cover against dislodgment from its proper position on the chest.

As the cover merely swings on its edge and is held in position by the tongue and slots which interengage but are unattached, the cover is separable and may be removed for cleaning by merely opening it and lifting the tongue 14 vertically out of the slots 11. Similarly it may be replaced by merely 80 inserting the tongue into the slots which serve to guide the cover to its correct position.

While a single continuous tongue 14 is preferable for strength and simplicity of 85 construction, and for the purpose of closing the crack between the edge of the cover and the edge of the opening 5, when the cover is closed, to prevent moisture from dripping through the crack, separate tongues, one for 90 each slot 11, are within the scope of the invention and are contemplated by the claims. Also the extensions 10 might be connected in which case the two members 8 would be made in a single piece and a single slot 95 would be formed between 8 and the edge of opening 5. These and other modifications are within the scope of the invention and are contemplated by the claims unless excluded by express limitation. 100

I claim:

1. In combination, a receptacle top having an opening, and a separable cover for the opening adapted to swing on one edge resting on the receptacle top, such pivot 105 edge registering with one edge of said opening, a tongue extending from the pivot edge of the cover through said opening, and a

tongue engaging projection fixed to the receptacle and projecting into said opening whereby to provide an open ended slot for the reception of the edge of said cover.

5 2. In combination, a receptacle top having an opening, and a separable cover for the opening adapted to swing on one edge resting on the receptacle top, such pivot edge registering with one edge of said opening, a single tongue extending along the pivot edge of the cover and terminating short of both ends thereof and projecting through the opening of the receptacle top, and a pair of projections fixed to the receptacle and projecting into said opening adapted to engage the ends of the tongue.

10 3. In combination, a receptacle top having an opening and a pair of spaced open ended slots disposed within the opening adjacent one side thereof and facing each other, and a separable cover swinging on one edge as a pivot, such pivot edge registering with one edge of said opening, a tongue extending from the pivot edge of the cover 15 through the opening and rearwardly under the edge of the opening when the cover is closed, adapted to close the crack between the pivot edge of the cover and the edge of the openings, the edges of said tongue engaging the respective slots.

20 4. In combination, a receptacle top having an opening, a member fixed to the receptacle top and projecting into the opening, said member comprising an element spaced 25 from the adjacent edge of the opening whereby to form an open ended slot therebetween, and a separable cover swinging on one edge as a pivot, having a tongue or projection extending through said slot.

25 5. In combination, a receptacle top having an opening, a pair of members fixed to the receptacle top adjacent the respective corners of the opening and projecting into the opening, said members having extensions forming with the side of the opening 30 a pair of spaced slots facing each other, and a separable cover swinging on one edge as

a pivot and having a tongue or projection engaging said slots.

50 6. In combination, a receptacle top having an opening, a pair of members fixed to the receptacle top adjacent the respective corners of the opening and projecting into the opening, said members having extensions forming with the side of the opening 55 a pair of spaced slots facing each other, both margins of said extensions being bent downwardly, and a separable cover swinging on one edge as a pivot and having a tongue or projection engaging said slots; the inner 60 bent margin of the extensions being adapted to engage the tongue when the cover is opened and to serve as a stop.

65 7. A receptacle top having an opening therein, a member formed of sheet material underlying and secured to said top adjacent an edge of said opening, said member projecting into the opening, and a part extending outwardly from one edge of said member and spaced from said edge, said part being substantially triangular in section with its apex directed downwardly.

70 8. A receptacle top having an opening therein, a member extending into said opening from one edge of the top, said member having a portion extending substantially parallel to said edge and spaced therefrom, said portion comprising parts projecting downwardly at an angle to the plane of said member.

75 9. A receptacle top having an opening therein, a plate underlying said top adjacent an edge of said opening and secured thereto, said plate extending into the opening, a part projecting from one margin of said plate and extending substantially parallel 80 to said edge, said part having its opposite edge portions projecting downwardly and meeting at a point below the plane of said top.

90 Signed by me at Boston, Massachusetts, this 30 day of December, 1919.

ERNEST L. CONDON.
